A. M. SAMOUR

WIND WHEEL AND METHOD OF MAKING

Filed Jan. 24, 1925

UNITED STATES PATENT OFFICE.

ANOUSH M. SAMOUR, OF BOSTON, MASSACHUSETTS.

WIND WHEEL AND METHOD OF MAKING.

Application filed January 24, 1925. Serial No. 4,538.

To all whom it may concern:

Be it known that I, ANOUSH M. SAMOUR, a citizen of the United States, residing at Boston, in the county of Suffolk and State 5 of Massachusetts, have invented certain new and useful Improvements in Wind Wheels and Methods of Making, of which the following is a specification.

This invention relates to wind wheels of 10 the type ordinarily employed for toys and has for an object to provide a new and improved method of constructing a new and improved wind wheel.

A further object of the invention is to 15 provide a method whereby the materials for the construction of the device are stamped out of the blank from which the vanes of the wheel are constructed for the purpose primarily of economy in manufacture but 20 also for the purpose of providing an opening in the blanks whereby the blanks are more successfully interwoven for the production of the completed wheel.

A further object of the invention is to 25 provide a method of constructing a wind wheel which consists in stamping out from two substantially square blanks identical or substantially identical members having openings extending from the corners of the 30 blanks generally toward the center but not following a radius and terminating adjacent the center in enlarged openings which produce rosettes or washers for use in the further construction of the wheel.

A further object of the invention is to 35 attach at the center the members so cut by the use of an eyelet and then rotating the members an eighth of a turn relative to each other whereby the cut portions of each blank 40 are interwoven with the cut portions of the other blank so that all of the extremities of both blanks or members are uppermost.

With these and other objects in view, the 45 invention comprises certain novel parts, elements, units, constructions, combinations and steps as will be hereinafter more fully described and claimed.

In the drawings:

Figure 1 is a view of the completed wind 50 wheel seen in front elevation.

Figure 2 is a view of the completed wind wheel largely in edge elevation, certain parts being broken away.

Figure 3 is a plan of the superposed 55 members cut from the blank on a scale larger than Figures 1 and 2.

Figure 4 is a view of the blanks connected at the center and rotated eighth of a revolution relative to each other and interwoven, the scale being the same as the scale of Figure 3.

Figure 5 is a plan view of one of the washers or rosettes which are stamped out of the blank at the time of forming the 60 vane units of the wheel and used in the further construction of the completed wheel as will be hereinafter more fully described.

Like characters of reference indicate corresponding parts throughout the several 70 views.

In the construction of the wind wheel which forms the subject matter of the present application, the individual units which are employed in the construction are stamped out and are identical in form. At 75 Figure 3 such a unit is shown at 10 and it is to be understood that, while the device is constructed of two units, such units are identical in form and in practice will be stamped out simultaneously.

The blank in the stamping is provided with an opening 11 extending from each corner toward the center, the side lines of said opening diverging as indicated at 12 at Figure 3 and terminating in an opening of 80 general circular form with scalloped edges, as indicated at 13, such opening forming a rosette or washer 14 as shown more particularly at Figure 5.

Similarly there are also center openings 85 15 formed in the units and perforations 16 at the extreme ends of the tongues provided by such openings, likewise a perforation 17 in the rosette or washer 14.

Two of the units 10, preferably though 90 not necessarily of different colors, are connected together at the openings 15 by means of an eyelet 18. The tongues 19 are then turned inwardly, each in series being superposed upon the other, so that all of the several perforations 16 of the two units register and a headed fastening member 20 is inserted through the registering perforations 16 and through the eyelet 18 so that the two blanks, interwoven as shown at Figure 4, then assume the position as shown at Figures 1 and 2. This fastening member 20 is attached to any convenient form of stick or handle 21 by which the device is held in the hand in operative position. For the purpose of operating more smoothly the fastening member is preferably inserted 100 105 110

through a sleeve or spacer 22 so that the wind wheel in its completed form is held spaced away from the stick 20. Preferably also for the purpose of ornamentation, a bead or like device 23 is impaled upon the fastening member 20 before it is inserted through the perforation 16 and likewise an ornamental device 24, taking the general form of a bow. To properly hold this assembly in position the washer 14 is interposed between the bead 23 under the bow 24. Other washers may also be employed as found necessary or desirable as a sufficient number of such washers will be stamped out of the openings 13 in the blanks when said blanks are formed.

For making the device still more attractive to children, a small bell 25 is mounted upon the fastening member 20 within the interior of the wheel so that as the wheel rotates and produces a vibration the bell will cause a jingling sound.

The corners of the sheets 10, which become the outer corners of the completed wheel, are rounded as indicated at 26. This adds to the beauty and attractiveness of the device and also performs a utilitarian function in that it prevents scratching or wounding of tender flesh by a possible engagement with the rapidly rotating sharp ends.

Of course, the device is held in the hand by the stick 20 or set in any position where the wheel faces the wind and by reason of the curvature of the vanes produced by turning inwardly the tongues 10 the wheel is caused to rotate by the movement of the air in the usual well known manner.

What I claim to be new is:

1. The method of making a wind wheel

consisting in stamping identical units corresponding generally to a square with openings extending inwardly from the corners toward the center and diverging and merging into a scalloped inner enlarged opening, two of said units being connected together at their centers by an eyelet and given an eighth of a turn with the cut out portions of each interwoven with the other, turning in the uppermost ends of the interwoven blanks and connecting said inturned ends by a fastening member inserted therethrough and through the center eyelet.

2. The method of making a wind wheel consisting in stamping out of similar substantially square blanks a plurality of washers disposed upon a circle concentric with the center of said blank and continuing the openings formed by the cutting of said washers in converging lines to adjacent the corners of said blank and simultaneously stamping out from the center of the blank and from the tongues formed by the cuts adjacent the corner and from the washers perforations, interweaving two of said blanks by giving to one a one-eighth turn relative to the other and causing the like portions of the under to protrude through the openings of the upper, securing the two blanks together by an eyelet at the center, turning the perforated ends to bring all of said perforations into register, inserting a fastening member through one of said washers and through said registering perforations and through the eyelet, and attaching the end so inserted to a handle.

In testimony whereof I affix my signature.

ANOUUSH M. SAMOUR.
